J. H. HENSON

WIRE STRETCHER

Filed March 19, 1925

INVENTOR

James G. Henson

UNITED STATES PATENT OFFICE.

JAMES H. HENSON, OF FOSTER, OKLAHOMA.

WIRE STRETCHER.

Application filed March 19, 1925. Serial No. 16,688.

To all whom it may concern:

Be it known that I, JAMES H. HENSON, a citizen of the United States, residing at Foster, in the county of Garvin and State of Oklahoma, have invented a certain new and useful invention in Wire Stretchers, of which the following is a specification, reference being had to the accompanying drawings.

10 This invention relates to a wire-stretching machine, and has for its object the provision of a device which may be readily applied to and held in place at a post or may be located therebetween two posts for the purpose for mending broken strands between the said posts, and the invention also abounds in providing for the allowing of fastening the strands to any post intermediate of the fence or at the end of the fence.

20 Other objects of the invention will appear from a further and more complete reading of the following specification, drawing and the appended claims.

On the sheet of drawings accompanying and forming a part of this specification,

Figure 1 is an elevational view of a fence post and the invention in place,

Figure 2 is a similar view, the fence post being broken to shorten the view, and the reverse side of the machine being shown,

Figure 3 is a plan view of the invention showing the method of setting the machine when desired to splice broken strands,

Figure 4 is a similar view of the device set for wire stretching,

Figure 5 is a detail elevational view of an eye and

Figure 6 shows a convenient form of strand-clamp or clutch.

40 In these several views similar characters of reference indicate similar parts.

To a post 7 of any size, or shape or regularity or irregularity, it makes no difference, the invention is applied by a shoe constituted of flanges 8, 9 and 10 on either side, and which may if desired be so sharpened as to be able to bite into the post if the post be wooden, and, if cement, the flanges may be reshaped or set to hold in a proper manner to a cement post, and, as before stated, it makes no difference as to the shape of the post.

This shoe has a body 11—see Figures 3 and 4—and to this body is secured in any suitable manner, for instance by bolts 12 to the extended frame 13, and also carries a

hinged grip 14, the purpose whereof will be more fully set forth.

Upon a yoke 15 hinged into the eyes of the end ears 9 and 10 is movably mounted a headed lever 16 having a head 17 with a bifurcated beak 18 with a bifurcation 19 for taking a link 20 of a chain that is securable to a rope, wire or rod 21 that surrounds the post 7 in the gripping operation of holding the stretcher in place. This beak 18 is of course capable of taking into any of the links of a chain, which chain may be sufficiently long to allow for posts of different size, even trees where it is desired to fix the strand to a tree at one part of the fence line.

Through the framing 13 passes a crank shaft 22 having transverse openings 23 and 24, the latter being designed to receive the end of the strand 25 so that that end can be wound up on the shaft 22 during the stretching operation, the strand passing through an eye member 26 bolted to the frame 13 by a bolt 27, the eye body of the eyed member 26 being slotted at 28 and bears against the wall of the frame 13, but if, for any reason, it should be desirable to remove the strand after it has been threaded through the eye, the bolt 27 may be loosened and the eye body 26 may be removed from the wall of the frame 13, and the strand removed. After passing through this eye and the end of the strand wound upon the shaft 22 of the crank 29 which may be turned by a wooden handle 30 bolted by 31 to the crank, the strand may be stapled to the post. It is not always within the art to which this invention pertains to have an efficient stretcher with which and by which the stapling can be had while the stretcher is in place.

Intermediate of the length of the frame 13 is a clamp 32 constituted of two chucks 33 and 34, respectively, and adapted to be bolted to the frame 13 by a bolt 35. This clamp in ordinary stretching of the fence is not used, and therefore one of the chucks that marked 33 is set at right angles to the one 34. The operation here is that the framing and its parts are gripped to the post by causing the element 21, which may be wire, rope or rod to pass about the post 7, and be hitched in place by the beaked lever 16 passing into the link of the chain. The wire is threaded through the eye body 26 and wound upon the shaft 22, passing its end into one of the eyes 24, on that part of the shaft that extends out beyond the frame

13, and when this done the strand may be stapled to the post.

While this is being done, a pin 32 is passed through the openings 23 in the shaft 22 of which there are two and the same may be laid upon a bolt 33 for preventing the shafting from turning.

For the purpose of holding the device in different perpendicular positions, a hinged element 14 is provided with a hole 34 through which is passed a rod 35 having a spike 36 which may be driven into any part, either top or side of the upper part of the post seven, and when it is desired to raise or lower the device, the element 14 is simply set at right angles to the perpendicular of the rod and the rod and element 14 is allowed to slide relatively.

The lower end of the rod 35 is provided with an adjustable set piece for resting on the ground, this piece being numbered 36' and this piece prevents the rod from going too far into the ground.

This device when set in place, goes before the post and the strand as seen in Figure 2, and thus allows for the proper stapping of the strand to the post, whether in the fence line or at the end, it makes no difference.

When it is desired to splice broken strands the strands being broken between posts, the lever and beak 16 and 18 respectively is set to the position shown in Figure 3, the beak 18 being brought around with the yoke 15 to the point 10, see Figure 3, when a hook 37 engaging a spring 38 secured to the bolt 33 is hooked about the lever 16 and thus the lever is held in an inoperative position. At this time the device is placed at the splicing point between two posts, the strands 25 and 38 are passed through eyes 26 and 39 and clamped together in the clamp 32 and between the body of the eye-body 26 and the frame 13 which also provides for a clamp. The one strand is thus clamped between the frame 13 and body of the eye-body 26, by loosing and tightening again the bolt 27 and the other strand is wound on the shaft 22, and when drawn sufficiently tight is clamped in the chuck 32', the wire is released from the clamp 26, and from the shaft 22 and both ends are brought down underneath and as close to the clamp 32 as possible and tied together in any suitable manner.

Having thus set forth the invention, I claim:

1. A device of the kind, as set forth, constituting a frame, a shoe having prongs attached to the frame, yokes carried by the shoe, a lever mounted on the yoke, a beak having a bifurcation carried by the lever, a chain, a connection between chain and

the shoe, a crank shaft carried in the frame, a crank for the shaft, clamping elements carried by the frame, means for locking the shaft in different positions, and means for holding the lever in an inoperative position.

2. A device for splicing fence strands intermediate of posts consisting of a frame, a shoe, having prongs, a yoke movable in the prongs, a lever mounted in the yoke, a beak therefor having a bifurcation, a chain for passing about a post, and taking into the bifurcation, a hook when the lever is drawn to an inoperative position for holding same in that position, and a spring for said hook, and secured in position relative to the frame.

3. A device having a frame, clamps thereon, an eye member, one of the clamps and the eye member constituting two eyes, means for holding the same to a post, means to render said means inoperative at will, a spring to control said holding means, a shaft upon which to wind the strands, means to hold the shaft in positions, a crank for said shaft, and means when the lever is set in operative position to embrace the post and hold the device in fixed position at will.

4. A wire stretcher adapted to be set in position, means to hold same in different positions, means for clamping the same adjustably about posts and trees of different sizes, means adapted to hold said means in an inoperative position at will, clamps located on the elevating member, an eye formed physically thereon, one of said clamps also constituting an eye having an outlet, a shaft having strand eyes, and openings, and a pin passing through the openings for holding the shaft in various positions during strand winding.

5. A wire stretcher consisting of an elongated frame, having an opening for a shaft, a shaft having transverse openings, one of which is on the shaft and outside of the frame to receive the strand end, means to lock the shaft in winding position, clamps on said frame, one of which also constitutes a strand eye, and being adjustable, said eye having an eyelet, another eye, a shoe attached to the frame, cleats on said shoe, a yoke movable in the cleats, a lever fulcrumed on the yoke, a beak on the lever and having a bifurcation, a connection leading from the shoe, a chain leading from the connection and adapted to have its links one by one at will take into said bifurcation for holding the frame in place, and means to hold the device in different elevations.

Signed at Oklahoma, in the county of Oklahoma, and State of Oklahoma, this 14th day of March, in the year of our Lord, nineteen hundred and twenty-five.

JAMES H. HENSON.
